UNITED STATES PATENT OFFICE.

JOHAN ARON ALLING, OF STOCKHOLM, SWEDEN, ASSIGNOR OF ONE-THIRD TO HERMAN HUSBERG, OF STOCKHOLM, SWEDEN.

PEN.

No. 920,900.

Specification of Letters Patent.

Patented May 11, 1909.

Application filed November 26, 1907. Serial No. 403,902.

To all whom it may concern:

Be it known that I, JOHAN ARON ALLING, a citizen of the Kingdom of Sweden, residing at Stockholm, Sweden, have invented 5 new and useful Improvements in Pens, of which the following is a specification.

My invention relates to pens; and it has for its object to render the point portion of a pen more weak and yielding than heretofore. To the attainment of said object the invention consists in a pen in which the point-halves have one or more plane or flat portions the inner or rear ends of which are turned laterally outward, whereby the point-halves of the pen will be capable of yielding not only upward but also sidewise without being subjected to any special pressure, so as to allow a very smooth writing.

In the drawings, accompanying and forming part of this specification: Figure 1 is a plan view of a pen constituting a practical embodiment of my invention. Figs. 1^a and 1^b are enlarged, detail sections, taken in the plane indicated by the lines 1^a—1^a and 20 1^b—1^b, respectively, of Fig. 1. Figs. 2, 3 and 4, are views similar to Fig. 1 of modifications hereinafter referred to in detail.

Referring to Figs. 1, 1^a and 1^b, the two point-halves 1 and 2 are in connection with the other part of the pen by means of plane or flat portions 3 and 4, located at opposite sides of the usual central cut of the pen. At 30 their inner or rear ends the said plane or flat portions 3 and 4 are turned laterally outward so as to permit the point-halves 1 and 2 to yield sidewise at the same time as they yield upward when a very slight pressure is exerted on the pen in writing.

In the form shown in Fig. 2 the plane or 40 flat portions 3^a and 4^a are of substantially

the same shape as those in Figs. 1, 1^a and 1^b, but located at the outer edges of point-halves 1 and 2.

In the form shown in Fig. 3 the plane or flat portions 3^b and 4^b are located at the 45 middle of the point-halves 1^d and 2^d and do not extend to the outer edges thereof, nor to the central cut.

In the form shown in Fig. 4 the point-halves 1^e and 2^e have each plane or flat portions 5, 6 and 7, 8 respectively. The fore 50 two portions 5 and 7 are parallel to the longitudinal center of the pen while the two other portions 6 and 8 are turned laterally outward in relation to the portions 5 and 7, thereby allowing the point-halves 1^e and 2^e to yield side-wise.

In all the forms shown the plane or flat portions are limited by cuts more or less parallel to the usual central cut, and cross- 60 cuts may be made between the first mentioned cuts and the edges of the pen or the central cut or both.

Having now described my invention, what I claim as new and desire to secure by Letters Patent is:

A pen in which the point-halves have flat portions located at opposite sides of the cut between the said point-halves; the rear ends of the said flat portions being turned laterally outward, substantially as and for the purpose set forth.

In testimony whereof I have signed my name to this specification in the presence of two subscribing witnesses.

JOHAN ARON ALLING.
